UNITED STATES PATENT OFFICE

162,813

ELECTRICAL TEST PROBE

Gerald N. Goldberger, Flushing, and Victor I. Robinson, Far Rockaway, N. Y., assignors to Precision Apparatus Co., Inc., Elmhurst, N. Y., a corporation of New York

Application September 27, 1949, Serial No. 5,194

Term of patent 14 years

(Cl. D26—1)

To all whom it may concern:

Be it known that we, Gerald N. Goldberger and Victor I. Robinson, citizens of the United States and residents, respectively, of Flushing and Far Rockaway, in the county of Queens and State of New York, have invented a new, original, and ornamental Design for an Electrical Test Probe, of which the following is a specification, reference being had to the accompanying drawing forming a part thereof, in which:

Fig. 1 is a perspective view of an electrical test probe showing our new design;

Fig. 2 is a side elevation of the same;

Fig. 3 is a rear end elevation of the same; and Fig. 4 is a front end elevation of the same.

The dominant features of our design reside in that portion shown in full lines in the drawing.

We claim:

The ornamental design for an electrical test probe, as shown and described.

GERALD N. GOLDBERGER.
VICTOR I. ROBINSON.
